UNITED STATES PATENT OFFICE

2,473,343

CENTRIFUGAL SWITCH DEVICE

Georges Levesque du Rostu, Paris, France, assignor to Societe Anonyme Andre Citroen, Paris, France

Application July 20, 1945, Serial No. 606,226
In France June 27, 1942

Section 1, Public Law 690, August 8, 1946
Patent expires June 27, 1962

3 Claims. (Cl. 200—31)

1

My invention has for its object spark advancing control device for internal combustion engines and is intended to reduce the number of parts and to simplify the operations of assembly.

Said centrifugal switch device is based upon the centrifugal action of a mass carried by one or several springs secured without an intermediate fulcrum or like member at one end to the driving shaft and at the other end to the cam-shaft. By the action of the centrifugal force the mass tends to move away from the axis of rotation, thus causing the spring to deform elastically and the angular set of the driving shaft to vary with respect to the cam-shaft.

Preferably, the spring consists of a steel wire or the like formed at either end thereof with a loop received in a groove provided in each shaft. The mass is fitted on the spring so that it cannot swing thereabout.

According to one peculiarity of the subject matter of the invention the breaker arm together with the pivot and the adjustable contact are carried as a whole by a sheet-metal member received in an annular recess provided in the casing.

The simultaneous adjustment of the initial spring stress and of the lead magnitude is obtained by means of a ring member secured on the driving shaft and formed with abutments which are set with respect to each other at 180° plus the amount of the adjustable lead and which correspond to abutments spaced through 180° provided on the cam-shaft.

A preferred embodiment of the subject matter of this invention will now be more particularly described, reference being had to the appended drawings wherein:

Fig. 1 is a vertical cross-sectional view.

Fig. 2 is a plan view corresponding to Fig. 1, the upper cap being taken away.

Figs. 3, 4 and 5 show the timing device in front, side and plan view respectively.

Fig. 6 is a detail view of the timing device, while

Fig. 7 is a plan view of the upper side of the abutment ring-member of the same.

Fig. 8 is a similar view of the member cooperating with said ring member.

Fig. 9 shows a detail in cross-sectional view through a plane passing through the medial part of the mass.

Fig. 10 illustrates a detail of another form of securing the mass.

Essentially, the ignition device comprises the

driving shaft 1 and the cam-shaft 2 which drives the circuit breaker; the whole is housed in a casing 5 on which the adjusting device 6 is mounted.

5 The ignition control mechanism (Figs. 3, 4 and 5) comprises a driving shaft 1 alined with the cam-shaft 2. The angular set of these shafts with respect to each other is obtained by means of one or several symmetrical springs 7. Each spring is secured at one end to shaft 1 and at the other end to shaft 2.

10 Preferably, the spring consists of a steel wire formed at either end thereof with a loop 8 received in a groove 9 in the shaft; a pin 26 fitted in a recess 27 (Fig. 9) or a flat portion 28 (Fig. 10) retains the loop from slipping in the groove and moving about the shaft.

15 Said spring is curved at the place where the mass 4 is attached, same being made for instance of two halves provided with a groove having the same radius of curvature R as the spring and assembled by means of rivets 10. As shaft 1 rotates the mass or masses 4 by the action of the centrifugal force will tend to move away from the axis of rotation which results in an elastic deformation of the spring and a shifting of the driving shaft with respect to the cam-shaft, and consequently a variation of the angular set.

20 Breaker arm 11, pivot 12 and adjustable contact 6 are carried as a whole by a sheet-metal member 13 secured by a screw 14 to the casing 5 (Fig. 2). For that purpose, said casing is formed with an annular recess 15 in which the sheet-metal member 13 is fitted; said recess also retains 25 the cardboard insulator 16 of the leading-out terminal 17. It is to be noted that the breaker arm 11 is operated by cam 11' formed on part 3 (see Figures 1 and 2).

25 The sheet-metal member 13 is bent at its end 40 18 to carry the pivot 12 of the circuit-breaker. Tapped at its other end is a hole 20 for the tungsten-contact set screw.

30 For defining the starting point and the extent of the lead it is only necessary to adjust the tension of spring 7.

35 In the case of an ignition control device with no secondary timing it is possible to modify together the starting point and the extent of the lead. To this end the circuit breaker rigid with cam-shaft 2 is formed with two abutments 21 corresponding to the abutments 22 on ring-member 23 secured on the driving shaft 1. The abutments A on shaft 2 are set at 180° from each other, while the angular spacing of the abutments on shaft 55 1 is 180° plus the desired lead magnitude. A sim-

ple operation in either direction of washer 25 is sufficient for adjusting the lead.

Ring-member 23 is provided with an adjusting slot 24. In order to retain said ring from being carried with as the locking nut is being tightened, provision is made between said ring-member 23 and the nut of a washer 25 formed with a flat portion fitting a corresponding flat portion machined on the threaded end of shaft 1.

What I claim as my invention and desire to secure by Letters Patent is:

1. An automatic spark advancing mechanism for internal combustion engines including at least one mass submitted to centrifugal force, formed by two superposed symmetrical members showing a groove in the cooperating surfaces thereof, a spring to which said mass is directly secured, a driving shaft, a cam shaft the angular shifting of which with reference to the driving shaft defines the variation in the lead and means for securing the ends of the spring respectively to said two shafts, the radius of curvature of the spring in the part to which the mass is secured matching the radius of curvature of the groove.

2. An automatic spark advancing mechanism for internal combustion engines including at least one mass submitted to centrifugal force, a yielding wire ending with a loop at each end, a driving shaft, a cam shaft the angular shifting of which with reference to the driving shaft defines the variation in the lead, each of said two shafts being provided near their cooperating ends with an annular groove in which the corresponding

looped end of the wire is inserted and a recess opening in said groove and a stud carried at the end of each loop and adapted to fit the recess in the corresponding groove holding the wire end considered for preventing any free rotation of said loop.

3. An automatic spark advancing mechanism for internal combustion engines including at least one mass submitted to centrifugal force, a yielding wire ending with a loop at each end, a driving shaft, a cam shaft the angular shifting of which with reference to the driving shaft defines the variation in the lead, each of said two shafts being provided near their cooperating ends with an annular groove in which the corresponding looped end of the wire is inserted, said spring ending with flat ends, each shaft including a flat part for engaging the corresponding flat end of the spring and preventing any rotation of the spring round the shaft considered.
